UNITED STATES PATENT OFFICE

163,028

STIRRING AND BEATING SPOON

James E. Donaldson, Chicago, Ill.

Application June 22, 1948, Serial No. 147,131

Term of patent 14 years

(Cl. D44—29.4)

To all whom it may concern:

Be it known that I, James E. Donaldson, a citizen of the United States and resident of Chicago, in the county of Cook and State of Illinois, have invented a new, original, and ornamental Design for a Stirring and Beating Spoon, of which the following is a specification, reference being had to the accompanying drawing, forming a part thereof.

In the drawing,

Figure 1 is a front elevational view of a spoon, showing my new design; and

Figure 2 is a side elevation of the spoon.

This spoon is characterized by a bowl having a forward edge extending obliquely across it with a cut-out design in the bowl itself.

The dominant feature of my design resides in the portion shown in full lines in the drawings.

I claim:

The ornamental design for a stirring and beating spoon, as shown and described.

JAMES E. DONALDSON.
